UNITED STATES PATENT OFFICE

SALVATOR CEFALU AND ANDREW CEFALU, OF BROOKLYN, NEW YORK

PERMANENT WAVING APPARATUS

Application filed December 15, 1930. Serial No. 502,542.

This invention relates to a hair waving device and more particularly to an apparatus for producing a wave of the "permanent" variety.

In practically all of the permanent waving machines presently in use the hair is wound around a number of tubular curlers and a suitable cover is then placed over same. Heating means, disposed either within the curler or in the cover structure, is employed to produce the curl. The objection to this type of wave is that it must be repeatedly "set" in order to look well.

The object of the present invention is to provide a hair waving device wherein the hair is curled in the same position as the position in which it will lay on the head, with the result that it will never need "setting".

Another object of the invention is to provide a hair waving device which will largely eliminate the discomfort, and in many cases pain, caused by the present machine.

Still another object of the invention is to provide a permanent waving device which is inexpensive to construct and so simple in operation that a relatively inexperienced operator may produce a beautiful wave.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings which latter shows embodiments of the invention as at present preferred.

In said drawings:

Fig. 1 is a top plan view of the embodiment, practically in section.

Fig. 2 central vertical section of same.

Fig. 3 is a section on line 3—3 of Fig. 2.

Fig. 4 is a perspective view of the clamping means.

Fig. 5 is a perspective view of one of the parts.

Fig. 6 is a perspective view of the clamp for securing the end of the hair.

Referring now more particularly to said drawings, the embodiment, as at present preferred includes an upper clamping structure 10 and a lower clamping structure 11, both of which are constructed of suitable sheet metal and are hollow. The clamping structure 10 has a flat upper surface 10'.

The lower ends of the corrugations on the upper clamping structure are provided with a concave surface, as indicated at 12' in Fig. 2, in order to provide space for a clamp hereinafter described. A suitable electrical heat unit 13 is disposed within said structures 10 and 11 in such a manner as to evenly heat all parts of the lower surface 12. A suitable electric connecting plug 13' is connected to the unit 13.

The lower clamping structure 11 is provided with a flat lower surface 11' and a corrugated upper surface 14.

The hair enters the device as at 16. Inasmuch as it will be necessary to clamp the hair tightly within the corrugations, a clamp 17, having a convex lower side is secured to the concave portion 18 by any suitable means, thereby holding the hair, which passes therebetween.

It will be clear that the hair is completely bound within the lower clamping structure before the upper one is secured thereto. As the hair is passed down the first corrugation a roller 19 is placed over same, said roller being held in place by means of a clamp 20, normally held in place by a coiled spring 20'. The hair is then brought up to the crest 21 of this corrugation and an angle piece 22 which is of the same width as that of the clamping structure is placed over said hair. The hair is likewise passed over the succeeding corrugations until the last roller 23 is reached, said roller being provided with a spring clamp which holds the ends of the hair.

The upper clamping structure is now placed upon the lower one and U shaped clamp 24 having threaded upper ends 25 and carrying wing nuts 26 which engage a cross bar 27, is placed at each end of the clamping structures and said wing nuts are tightened.

The clamps 20 are then removed, as indicated in the broken lines in Fig. 3 and the heat applied. It will be appreciated that the number of embodiments necessary to wave the entire head at one time will vary somewhat according to the amount of hair.

The hereinbefore described construction admits of considerable modification without departing from the invention; therefore, it is the wish not to be limited to the precise arrangements shown and described, which are as aforesaid by way of illustration merely. In other words the scope of protection contemplated is to be taken solely from the appended claim interpreted as broadly as is consistent with the prior art.

What is claimed as new is:—

20 A hair waving device including an upper and a lower clamping structure, said clamping structure having a plurality of corrugations on one side thereof to engage the hair therebetween, heating means disposed within said clamping structures, a plurality of rollers for engaging the hair at the lower 25 portion of the corrugations in the lower clamping structure and clamps for securing said rollers, a plurality of removable clamps for engaging the hair at the crest of the corrugations in said lower clamping structures 30 and means for holding said clamping structures together.

In testimony whereof we hereby affix our signatures.
